UNITED STATES PATENT OFFICE.

JAMES E. KENNEDY, OF WASHINGTON, DISTRICT OF COLUMBIA.

GAS-HEATED STOVE.

1,189,699.

Specification of Letters Patent.

Patented July 4, 1916.

Application filed July 30, 1915. Serial No. 42,824.

To all whom it may concern:

Be it known that I, JAMES E. KENNEDY, a citizen of the United States of America, residing at Washington, District of Columbia, 5 have invented certain new and useful Improvements in Gas-Heated Stoves, of which the following is a specification.

This invention relates to stoves and has especial reference to an apparatus designed to 10 automatically control the fuel supply to gas heated stoves.

A principal object of the invention is to improve and simplify the general construction of controlling devices for stoves of this 15 character, and position the actuating mechanism away from the burner blaze.

A second object of the invention, and also an important one, is to provide means whereby vessels having differently shaped bottoms 20 may be seated over the burner of such a stove and at the same time produce the desired supply of fuel by such heating.

A third important object of the invention is to provide a stove of this description with 25 a water jacket so arranged that the excess heat or waste heat will be absorbed by the jacket.

A fourth important object of the invention is to provide a water jacket of this description wherein the major portion of the heat will be utilized for heating a vessel above the stove while the waste heat will be utilized in the production of heat in a water jacket.

35 With the above and other objects in view, as will be hereinafter set forth, the invention consists in general of certain novel features of construction and combinations of parts hereinafter fully described, illustrated 40 in the accompanying drawings and specifically claimed.

In the accompanying drawings like characters of reference indicate like parts in the several views.

45 Figure 1 is a longitudinal section through a burner of a stove constructed in accordance with this invention. Fig. 2 is a top plan view of such a burner and a portion of the stove surrounding the same. Fig. 3 is a 50 perspective view of the part arranged to turn or operate the valve in such a stove. Fig. 4 is a perspective view of a lever arranged for connection to the part shown in Fig. 3. Fig. 5 is an inverted perspective

view of the support or actuating member for 55 the valve control controlled by the vessel.

Referring more particularly to the several figures shown in the drawing there is provided a burner 9 of the general type used in gas stoves. A water top is disclosed with an 60 outer casing 10 having spaced therefrom a wall 11 and a top 12 inclined downwardly to the center of the casing 10. This casing, 65 wall and top form a water chamber 13 which is provided with an inlet 14 and outlet 15 so that water can be constantly circulated through the chamber 13. Moreover, the casing 70 is provided with a centrally arranged opening 16 about which are arranged flame openings 17 and between these flame openings 75 are the water circulating passages 18 forming extensions inwardly of the chamber 13. Beneath this water chamber is arranged the burner 9 which consists of a main chamber 19 having under the passage 18 perforations 80 for the escape of the gases when burning. This chamber 19 is supplied with a combustible mixture of gas and air through a tube 21 which is supplied with gas through a tube 22 provided with a cut off valve 23 and also 85 with a mixing valve 24. This mixing valve is controlled by a lever 25 whereto is connected one end of a link 26 having its remaining end connected to one arm of a rock shaft 27 formed of a single length of rod. 90 This rock shaft, indicated in general at 27 and specifically shown in Fig. 4, consists of a body portion 28 having an arm 29 terminating in an eye 30 which is connected to the link 26 and also having an arm 31 from 95 which extends a straight portion 32 terminating in a portion 33 extending at right angles to the portion 28 and having a hook 34 on its end. This hook 34 engages the loop 35 of an actuating lever consisting of a single 100 length of rod whereof the loop 35 forms the medial portion and from this loop 35 extends a pair of parallel arms 36 which are bent upward, as at 37, to pass through a rock shaft 38 journaled in lugs 38' on the rear 105 wall of the casing. These arms pass through the rock shaft at right angles to the upwardly bent portions 37 and terminate in portions 39 which extend through a counterweight 40 shiftable on the arms for the purpose of increasing or decreasing the resistance desired. The body portion 28 of the 110 said rock shaft 27 is journaled horizontally

beneath two lugs 66 carried inwardly of a forward flange 67 of the stove, while a retaining plate 68 is secured to the lower face of the said lugs by screws 69.

Extending downward from the valve 24 is a casing 40' from whence extends a pilot tube 41 having a sleeved connection 42 with a pilot burner 43 extending up through the central opening 16' of the burner. In order to actuate the lever formed by the arms 36 these arms are connected to a U-shaped loop 44 of inverted character and on the upper end of this loop is carried a pin or tube 45 having extending from one side thereof a lug 46. On this pin or tube is seated a depressing element which extends above the upper surface of the stove and consists of radial arms 47 connected to a hub 48 having a series of slots 49 formed therearound, these slots being of different depths so that by lifting this member and rotating the same to bring one or the other of said slots in alinement with the lug 46 the depressing element may be arranged in suitably spaced relation to the top of the stove and thus accommodate either flat, convex, or concaved bottom vessels when placed thereon.

In operation the stationary pilot light is at all times supposed to be burning. After the member 48 has been adjusted for height as previously described, the vessel may be placed thereon and will depress the member 44 and consequently actuate the lever 36, so that as the latter turns about the axis of the axle 38 the valve 24 will be actuated and the gas supply turned on. It is noted that all of the automatic operating means for the valve 24 including the elements shown in Figs. 3, 4 and 5 are located entirely out of the path of the blaze from the burner 9.

For the purpose of controlling the escape of heat from one burner to an adjacent burner there is provided a damper 50 in one of the side walls of the casing which is controlled by a headed rod 51 extending through said casing.

While the form of the invention herein shown and described is what is believed to be the preferred embodiment thereof, it is nevertheless to be understood that minor changes may be made therein without departing from the spirit and scope of the invention as claimed.

What I claim as new is:—

1. A stove comprising a grid, a burner having a mixing tube and positioned beneath the said grid, a valve for the said burner, a rocking operating lever consisting of a single length of rod having a transversely arranged upstanding loop at the forward end thereof encircling the said mixing tube, operative connections between the said loop and valve, and contacting means carried by the said lever and normally extending above the said grid, the said lever

being arranged entirely beneath the level of the burner top.

2. In a gas stove, the combination with a burner; of a cock for governing the supply of gas to the burner, and means controlled by the imposition of a cooking vessel thereon for opening and closing said cock, said means including a lever provided intermediate its ends with an upstanding member terminating in a pin having a lug on one side thereof and a support rotatably mounted on the lug and provided with a spaced series of slots of different depths, said slots engaging the lug to regulate the height of said member. 80

3. In a gas stove, the combination with a burner; of a cock for governing the supply of gas to the burner, and means controlled by the imposition of a cooking vessel thereon for opening and closing said cock, said means including a lever provided intermediate its ends with an upstanding member terminating in a pin having a lug on one side thereof and a support rotatably mounted on the lug and provided with a spaced series of slots of different depths, said slots engaging the lug to regulate the height of said member, said member further consisting of a central body wherein said slots are formed and downwardly inclined radial 95 arms. 90

4. In a device of the class described, the combination with a grid, of a burner mounted beneath said grid and provided with an annular body and a mixing tube, a gas supply pipe extending into the tube, a cock in said gas supply pipe, a rock shaft mounted adjacent the front of the device and provided with a downwardly extending arm, a lever attached to said cock to control the same, a link connecting said arm and lever, a forwardly extending arm on said rock shaft provided with a hook at its forward end, and an operating lever journaled at the rear of the device and operatively connected to said hook. 100 105

5. In a device of the class described, the combination with a grid, of a burner mounted beneath said grid and provided with an annular body and a mixing tube, a gas supply pipe extending into the tube, a cock in said gas supply pipe, a rock shaft mounted adjacent the front of the device and provided with a downwardly extending arm, a lever attached to said cock to control the same, a link connecting said arm and lever, an inwardly extending arm on said rock shaft provided with a hook at its inner end, a second rock shaft journaled at the rear of the device, a lever consisting of a single length of rod having an upstanding loop at one extremity engaged with the hook on the first mentioned rock shaft and embracing the mixing tube, said lever further comprising rearwardly extending portions lying beneath 110 115 120 125 130 135

the tube and burner and terminating in upwardly and rearwardly extending portions passing through the second rock shaft, and a counter-weight carried by the last mentioned 5 portions of the lever.

6. In a device of the class described, the combination with a grid, of a burner mounted beneath said grid and provided with an annular body and a mixing tube, a gas supply pipe extending into the tube, a cock in said gas supply pipe, a rock shaft mounted adjacent the front of the device and provided with a downwardly extending arm, a lever attached to said cock to control the 10 same, a link connecting said arm and lever, an inwardly extending arm on said rock shaft provided with a hook at its free end, a second rock shaft journaled at the rear of the device, a lever consisting of a single 15 length of rod having an upstanding loop at one extremity engaged with the hook on the first mentioned rock shaft and embracing the mixing tube, said lever further comprising rearwardly extending portions lying beneath the tube and burner and terminating in upwardly and rearwardly extending portions passing through the second rock shaft, a counter-weight carried by the last-mentioned 20 portions of the lever, and means controllable by the imposition of a vessel on the device for moving said lever.

7. In a device of the class described, the combination with a grid, of a burner mounted beneath said grid and provided with an annular body and a mixing tube, a gas supply pipe extending into the tube, a cock in said gas supply pipe, a rock shaft mounted adjacent the front of the device and provided with a downwardly extending arm, a lever attached to said cock to control the 25

same, a link connecting said arm and lever, an inwardly extending arm on said rock shaft provided with a hook at its forward end, a second rock shaft journaled at the rear of the device, a lever consisting of a 45 single length of rod having an upstanding loop at one extremity engaged with the hook on the first mentioned rock shaft and embracing the mixing tube, said lever further comprising forwardly extending portions 50 lying beneath the tube and burner and terminating in upwardly and rearwardly extending portions passing through the second rock shaft, a counter-weight carried by the last-mentioned portions of the lever, and 55 means controllable by the imposition of a vessel on the device for moving said lever, said means comprising a support extending upward through the burner from said lever and a vertically adjustable member carried 60 by the support.

8. A stove comprising a burner, spaced lugs forwardly positioned beneath the said stove, a rock shaft having a horizontal portion engaging the said lugs, a supporting 65 plate underlying the said body portion and secured to the said lugs, a valve for the said burner, operative connections between the said shaft and valve, a second rock shaft journaled at the rear of the stove, a lever secured to the rearwardly positioned rock-shaft, and consisting of a single length of rod having a forward loop operatively connected to the first-named rock shaft, and means controllable by the imposition of a 70 vessel upon the stove for moving the said lever.

In testimony whereof I affix my signature.

JAMES E. KENNEDY.
